UNITED STATES PATENT OFFICE

GEORGE B. COOK, OF ELIZABETH, NEW JERSEY, ASSIGNOR TO STANDARD OIL DEVELOPMENT COMPANY, A CORPORATION OF DELAWARE

FLUID HEATER

Application filed March 28, 1930. Serial No. 439,678.

This invention relates to a fluid heater and more particularly to an arrangement of the tubes and header boxes in the furnace so as to obtain a double circuit with equal heat input to each branch and equal flow through each branch of the double circuit. The invention will be fully understood from the following description read in conjunction with the drawings in which

10 Fig. 1 is a diagrammatic vertical section and elevation through part of the furnace, showing the arrangement of the tubes and flow of the fluid therein viewed from one side of the furnace;

15 Fig. 2 is a similar section showing the same arrangement and flow as seen from the other side of the furnace; and

20 Fig. 3 is a diagrammatic vertical section and elevation through the whole length of the furnace, showing the arrangement of the heating tubes according to the invention and their connection with the two sets of tubes in the convection heat section.

It is often necessary in fluid heaters to provide a double circuit of flow in the radiant heat section because one circuit of flow will require, at the given feed rate, too large a diameter of the tubes to be used with safety against bursting of the tubes under the desired conditions of temperature and pressure. It is, of course, a primary requirement that the heat input and fluid flow be equal in both branches of the double circuit. An advantageous arrangement of the tubes and the header boxes forms the subject matter of this invention, the main object of which is to provide such arrangement using two nearly horizontal rows of tubes, the individual members of the two rows being aligned in vertical direction to each other. When the invention is applied to cracking coils, used to heat the oil to cracking temperature, the following objects and advantages will be realized by the invention:

- 45 1. Equal heat input in each circuit.
2. Equal pressure drop in each circuit.
3. Equal velocity of the fluid in each circuit.
4. Equal throughout in each circuit.
- 50 5. Equal cracking in each circuit.

In the figures the numerals 1 and 2 designate the two circuits. One circuit includes a series of connected tubes 1a and 1b extending parallel to and spaced with respect to each other in vertically spaced substantially horizontal rows in the combustion chamber. The upper tubes 1b are connected to the lower tubes 1a in series by an appropriate fitting such as header boxes 3. A second series of similarly connected tubes 2a and 2b of substantially the same internal diameter as tubes 1a and 1b are disposed in the spaces between and substantially parallel with the tubes 1a and 1b in the rows. There may be two separate feed pumps 4 and 5 in the charging lines 6 and 7. Discharge lines 8 and 9 are shown connected to a common vessel 10, which in the case of cracking oils may be the so-called soaking drum. Each tube has a numeral 1 or 2 to designate the circuit to which the tube belongs, and a + or - sign to designate the direction of flow in the tube. The + sign means that the fluid flows away from the observer and the - sign means that the fluid flows toward the observer. The two rows are substantially horizontal and the individual tubes of the two rows are aligned in vertical columns of two tubes each with the possible exception of the extreme tubes which may have no corresponding tube in the other row. The flow in each branch of the double circuit is seen to be alternately through a top and bottom tube, the tubes of any one of the two rows being connected by header boxes to the tubes in the nearest columns of the other row. The flow in the two branches is always in adjacent tubes and preferably in the same general direction in the furnace to insure equal heat pick-up in the two branches. Considering only pairs of adjacent tubes in any one row the flow may be parallelly in the case of Fig. 1 but it could be opposite flow just the same.

Fig. 2 shows the same arrangement of tubes as Fig. 1 but the direction of flow in the individual tubes is observed from the other side of the furnace, that is from the left side if in Fig. 1 the flow was observed from the right side of the furnace.

In most cases the furnace is divided by a

55 60 65 70 75 80 85 90 95 100

bridge wall into a radiant heat section and a convection heat section. In such case the invention will be applied to the arrangement of the tubes in the radiant heat section.

5 In Fig. 3 the numeral 11 designates the radiant heat section, 12 the convection heat section of the furnace, separated from each other by the bridge wall 13. The tubes in the radiant heat section form a double circuit

10 designated by numerals 1 and 2 and ending in the discharge lines 8 and 9. The lines 6 and 7 are connected to two sets of tubes in the convection heat section, designated by numerals 14 and 15. The separate feed lines

15 16 and 17 of the two sets of tubes in the convection heat section may be connected to two separate feed pumps or may be fed by one pump if so desired.

The size and shape of all the header boxes 20 in the radiant heat section is exactly the same which, of course, is one of the advantageous features of the arrangement since it is not necessary to manufacture two or more different header boxes.

25 Having thus described my invention what I claim is the following:

1. Heat transfer apparatus, comprising a combustion chamber, a series of connected tubes extending parallel to and spaced with 30 respect to each other in vertically spaced substantially horizontal rows in the combustion chamber, the upper tubes being connected to the lower tubes in series, a second series of similarly connected tubes of the same internal 35 diameter as the first mentioned tubes and disposed in the spaces between and substantially parallel with the first mentioned tubes in the rows, means for delivering substantially equal quantities of fluid to the inlets of the series, 40 and means for discharging the fluid from the series.

2. Heat transfer apparatus, comprising a combustion chamber, a series of connected tubes extending parallel to and spaced with 45 respect to each other in vertically spaced substantially horizontal rows in the radiant heat section of the combustion chamber, the upper tubes being connected to the lower tubes in series, a second series of similarly connected 50 tubes of the same internal diameter as the first mentioned tubes and disposed in the spaces between and substantially parallel with the first mentioned tubes in the rows, means for delivering substantially equal quantities of 55 fluid to adjoining inlets of the series whereby the fluid flows through the pipes in parallel, and means for discharging the fluid from the series.

3. Heat transfer apparatus, comprising a 60 combustion chamber, a series of connected tubes extending parallel to and spaced with respect to each other in vertically spaced substantially horizontal rows in the combustion chamber, the upper tubes being connected in 65 series to and horizontally offset from the

lower tubes, a second series of similarly connected tubes of the same internal diameter as the first mentioned tubes and disposed in the spaces between and substantially parallel with the first mentioned tubes in the rows, means for delivering substantially equal quantities of fluid to the inlets of the series, and means for discharging the fluid from the series.

GEORGE B. COOK.
